United States Patent Office

Des. 176,041
Patented Nov. 8, 1955

176,041

COFFEE MAKER OR SIMILAR ARTICLE

Howard H. Schott, St. Paul, Minn., assignor to General
Mills, Inc., a corporation of Delaware

Application June 17, 1954, Serial No. 31,062

Term of patent 14 years

(Cl. D44—26)

FIG. 2

Fig. 3

Fig. 2 is a top plan view thereof;

Fig. 3 is a front elevational view, and

Fig. 4 is a rear elevational view of the coffee maker.

I claim:

The ornamental design for a coffee maker or similar article, as shown.
